ALCORN RECTOR, OF NEW YORK, N. Y., ASSIGNOR TO RECTOR GAS LAMP COMPANY, OF NEW YORK, N. Y., A CORPORATION OF NEW YORK.

GAS-LAMP.

957,476.

Specification of Letters Patent. Patented May 10, 1910.

Application filed July 6, 1909. Serial No. 506,216.

To all whom it may concern:

Be it known that I, ALCORN RECTOR, of the city, county, and State of New York, have invented a new and useful Improvement in Gas-Lamps, of which the following is a full, clear, and exact description.

My invention relates to improvements in gas lamps, and more particularly to so-called gas arc lamps, although the style of the lamp is not absolutely essential. My invention is, however, especially applicable to lamps which are generally arranged in series and which are adapted for store, hall, or street lighting more particularly, but as above stated, the improvement can be applied to various forms of gas lamps. The lamp to which it is best adapted is of the kind stated, and these lamps I have generally made with inclosed globes connected with an exhaust pipe and with a series of lamps connected with a single exhaust pipe, so that products of combustion will be exhausted from the globe and the fresh air allowed to flow in with the gas at the Bunsen tubes. Such lamps make a brilliant light, but they are apt to be rather inaccessible, and the object of my invention is to provide a simple means whereby such lamps can be automatically and simultaneously lighted or turned down, and to provide means of this nature which will also permit of individual lamp control. In carrying out this idea, I provide a small pilot jet for each lamp, which is kept burning, and have the main gas inlet to each lamp closed by a float valve so that when the exhausting means is not in operation the float will drop and the main gas supply be shut off, but when the exhausting means is started, the partial vacuum caused will cause the several floats to rise and permit the gas to flow readily and light the lamp. Obviously this idea can be carried out as applied to one lamp or to a whole series of lamps, but it is usual to apply the invention to a series of lamps, and the character of the lamps can be varied indefinitely, so long as they have exhausting means by which the float can be operated.

The invention will be fully understood from the description which follows.

Reference is to be had to the accompanying drawings forming a part of this specification, in which similar reference characters indicate corresponding parts in all the views.

Figure 1 is a side elevation of a type of lamp having my improvements applied thereto. Fig. 2 is an enlarged detail sectional view showing the arrangement of the float valve, and Fig. 3 is a cross section on the line 3—3 of Fig. 2.

The gas lamp 10 can be of any approved kind, but as stated is usually of the inclosed arc type having a globe 11 which rests on a suitable gallery 11^a, and an exhaust pipe 12 which delivers to a main pipe 13, and the latter can connect with any number of lamps and with an exhaust fan or other means for exhausting the gases from the globe 11. The lamp is equipped with a mantle 14, but obviously any number of these mantles can be used, and any preferred form of mantle or any means of supporting them can be adopted without affecting the principle of my invention. The main gas supply for the mantle or mantles flows in through a Bunsen tube 15, and a small pilot tube 16 also leads in to the lamp above the Bunsen tube, and is permitted to have sufficient gas flow to maintain a tiny gas flame at the base of the mantle. The pilot tube 16 can connect with the main supply in any suitable way, but I have found a convenient connection to be by means of the short tube 17 and valve 18, the connection being with the main gas supply pipe 19, and this is preferably though not necessarily dropped from overhead. The main pipe 19 supplies the Bunsen tube 15, and the gas supply is controlled by a common form of cock or valve 20.

Above and forming an extension of the Bunsen 15, is a cylinder 21 in which is arranged a float 22 which is preferably provided with perforations 23 through which the gas can pass, and the wall of the cylinder is also inclined outward on the inner side as shown at 24, so that when the float is raised to the position shown by dotted lines in Fig. 2, the gas can flow along the edge of the float. The float has a stem 25 which extends through a suitable guide 26, and the lower end of the stem terminates in a valve 27 which seats in the gas opening 28 which supplies the lamp. Under normal conditions the float 22, together with the stem 25 and valve 27 are sufficiently heavy to overcome the weight of gas pressing against the small valve in the restricted opening 28, but when a partial vacuum is created

in the globe 11 by starting the exhausting means connected with the pipes 13 and 12, the float 22 rises induced by the lessening of pressure on the back of the valve 27, 5 and so the gas supply flows freely in and as it enters the globe is ignited from the pilot flame issuing from the tube 16. It will thus be seen that the lamps are all controlled by the stopping and starting of the exhausting means connected with the exhaust pipe. 10 It will also be seen that any particular lamp can be cut out or in as desired by means of the valve 20, as usual.

From the foregoing description it will 15 be seen that I have provided a very simple and positive means for rendering gas lamps automatic as to their lighting, and that each individual lamp is perfectly controlled. It will also be understood that the style of 20 lamp has nothing to do with the invention except that it must be of such a nature as to permit of at least a partial exhaustion so as to cause the operation of the valve 27. The style of float 22 and the particular type 25 of valve and its support, is not, however, essential, although I prefer the forms indicated.

It will be noticed that some of the details of construction can be changed, as, for instance, the cylinder 21 can be a casing or other form, and also that the invention is applicable to any kind of lamp in which a globe or chimney is employed.

Having thus fully described my invention, 35 I claim as new and desire to secure by Letters Patent:-

1. A gas lamp, having a globe, a pilot burner for the lamp, a gas supply pipe for the lamp, means for exhausting the globe, 40 and a valve actuated by the change of pressure in the globe and controlling the gas supply.

2. The combination with a gas lamp having a globe and its gas supply pipe, of exhausting means connected with the lamp globe, and a valve operated by the starting and stopping of the exhaust and controlling the gas supply.

3. The combination with a gas lamp having a globe and its supply pipe, of exhausting means connected with the globe, a pilot tube leading from the gas supply pipe to the

lamp, and a valve controlling the main gas supply to the lamp, said valve being operated by the stopping and starting of the exhausting means. 55

4. The combination with a globe gas lamp having exhausting means connected with the globe, and a main gas supply pipe, of a pilot tube connecting the main gas supply pipe 60 with the lamp, a float supported above the gas supply pipe and between it and the lamp, and a valve carried by the float and seating in the gas inlet.

5. The combination with a globe gas lamp, 65 its main gas supply pipe, and means for exhausting the globe, of a pilot tube connecting the main gas supply pipe with the lamp, a casing forming a part of the gas inlet to the lamp, a float movable in the casing, and a valve carried by the float and seating in the gas inlet. 70

6. The combination with a series of globe-carrying lamps, of a common gas supply pipe for the lamp series, a common exhaust 75 pipe connected with the several globes, a pilot tube leading to each lamp from the gas pipe, and a valve controlling the gas supply to each lamp, said valve being operated by the stopping and starting of the lamp exhaust. 80

7. The combination with a series of gas lamps having globes and a common exhaust pipe for the lamp globe series, of a gas supply for the lamps, a pilot tube connecting each lamp with its gas supply, a valve controlling the gas supply to each lamp, and means for operating the valve by the stopping and starting of the exhaust. 85

8. The combination with a series of globe gas lamps, of a common exhaust pipe connected to the globes, a gas supply for the lamps, a pilot tube connecting each lamp with its gas supply, a manually operated valve controlling the main gas supply to each lamp, and a second valve for each lamp controlling its gas supply, said second valve being operated by the stopping and starting of the exhaust. 95

ALCORN RECTOR.
